HEMMING ATTACHMENT FOR SEWING MACHINES

John P. Enos, Union, N. J., assignor to The Singer Manufacturing Company, Elizabeth, N. J., a corporation of New Jersey

Application November 19, 1940, Serial No. 366,199

5 Claims. (Cl. 112—141)

This invention relates to useful improvements in sewing machine hemming attachments generally, although more particularly to a hemmer of the scroll and arbor type for forming an extremely narrow hem.

In using attachments of this type considerable difficulty is occasioned at times in hemming fabrics having cross-seams therein. In traversing such cross-seams the hemmer frequently becomes choked or clogged, inasmuch as the desirably small capacity of the attachment is exceeded by the relatively thick cross-seam. In view of this clogging, it has become common practice to provide hemmers with resiliently supported sections adapted to yield under the influence of variations in the thickness of the fabric being hemmed. These sections, in the majority of cases, are adapted to yield in a direction normal to the line of seam-formation and in order for these sections to so move considerable pressure must be applied thereto by the cross-seam which has the effect of impeding the progress of the fabric through the hemmer. The sewing machine feed-dog operates to overcome the impedance of the fabric, but in so doing effects a distortion of the fabric margin comprising the hem-fold, resulting in imperfections in the finished seam.

It is the primary object of the present invention to provide a hemmer having a scroll and arbor, wherein the scroll is yieldingly supported for movement in an arcuate path away from the arbor and in a direction inclined rearwardly and away from the normal line of seam-formation.

A further object of the present invention is the provision of a simple and effective means for yieldingly supporting the scroll member of a hemming attachment, whereby the capacity of the attachment can be automatically varied to accommodate fabrics having thickened portions therein, such as cross-seams or the like.

The invention further relates to arrangements and combinations of parts which will be more fully described hereinafter, pointed out in the appended claims and illustrated in the accompanying drawing, in which—

Fig. 1 is a perspective view of a hemmer foot embodying the invention and shown as applied to a sewing machine.

Fig. 2 is a top plan view of the improved hemmer.

Fig. 3 is a bottom plan view of the hemmer.

Fig. 4 is a right side elevational view of the hemmer.

Fig. 5 is a top plan view of the hemmer-scroll and its pivotal carrier-arm.

Referring more in detail to the drawing the preferred embodiment of the invention comprises a presser-foot hemmer including a base-member or sole-plate 1 having a shank 2 secured by a thumb-screw 3 upon the lower end of the usual presser-bar 4 of a sewing machine having a throat-plate 5 and a reciprocatory needle-bar 6 carrying the needle 7. The sole-plate 1 at its forward end is bifurcated to provide spaced toes 8 and 9, and is apertured, as at 10, to provide the usual needle-hole.

Soldered or otherwise suitably secured to the toe 8 is the shank 11 of an arbor 12, the free end of which is directed toward the needle-hole 10. The arbor 12 is preferably conical in shape in order that it will be sufficiently large in cross-section at any one point within its work-controlling length as to fill the tubular fold of fabric formed by the hemmer. By thus filling the tubular fold the same is prevented from collapsing prematurely, with the result that the tendency of the raw edge of the fabric to uncurl is reduced to a minimum.

Cooperating with the conical arbor 12 is the usual hemmer scroll 13 having a leading edge 14 which extends spirally rearwardly between the toes 8 and 9 toward the needle-hole 10. The scroll 13 is initially arranged in close proximity to the conical arbor 12 to effectively control thin fabrics. When so constructed, the hemmer will expeditiously handle thin fabrics, but at the same time it is susceptible of choking in the event 35 a cross-seam or the like enters the hemmer. To eliminate this choking the hemmer scroll 13 is supported so that it may yield bodily in an arcuate path away from the arbor 12 in a direction inclined rearwardly with respect to 40 the direction of the normal feed of the work through the hemmer. To this end, the scroll 13 is soldered or otherwise secured to the forward end of a pivotal carrier-arm 15 fulcrumed intermediate its ends upon a vertical pivot-stud 45 16 threaded into a lateral extension 17 integral with the sole-plate 1. At its rearward end the carrier-arm 15 is enlarged and formed with an elongated slot 18 entered by a stop-screw 19 also threaded into the lateral extension 17. The 50 ends of the elongated slot 18 cooperate with the shank of the stop-screw 19 to limit the swinging movement of the scroll 13. The scroll 13 is maintained in its normal operative relation with the arbor 12 by a spring-wire 20 coiled about 55 the pivot-stud 16 and having one of its ends

anchored in an aperture 21 in the carrier-arm 15 and its other end anchored in an aperture 22 provided in the lateral extension 17.

It will be understood that as a cross-seam in the fabric, indicated as S in Fig. 1, is drawn into the hemmer, the thickened portion of the fabric engages the spiralled edge 14 of the hemmer scroll 13 and acts to shift the scroll away from the arbor 12 in an arc about the axis of the pivot-stud 16, thereby to increase the capacity of the hemmer. After the cross-seam S passes beyond the hemmer, the scroll 13 returns to its normal operating position under the action of the spring-wire 20.

It will be observed in Fig. 2 that the pivot-stud 16 is disposed to the right of the needle-hole 10 and between the needle-hole and the receiving end, or mouth, of the hemmer. When located in this position, the initial arcuate movement of the scroll 13 about the axis of the pivot-stud 16 is in a direction inclined rearwardly and away from the line of seam-formation. When the scroll 13 moves in this direction, there is a component of movement normal to the line of feed and a component of movement parallel to the line of feed. The effort required to shift the scroll circularly in a rearwardly inclined direction is materially less than that required to shift the scroll in a direction normal to the line of feed, as is the usual direction of the movement of the scroll in prior attachments of this type. The resultant reduction in the effort required to shift the scroll lessens to a large extent the resistance to the passage of the fabric through the hemmer, with the consequence that the distortion of the marginal portion of the fabric adjacent the cross-seam is minimized.

From the foregoing description, it is obvious that the present invention contemplates an improved hemmer attachment having a variable capacity automatically regulated by the thickness of the fabric being hemmed, the scroll of the hemmer being supported in such a way as to offer a minimum of resistance to the passage of the fabric through the hemmer.

Having thus set forth the nature of the invention what I claim herein is:

1. A sewing machine hemming attachment comprising a base-member, an arbor fixed to said base-member and disposed so that its free end extends substantially in the normal direction of feed, a work-folding scroll complementary to said arbor, a carrier-arm sustained upon said base-member and supporting said work-folding scroll for movement relative to said arbor in a direction inclined rearwardly and away from the normal line of seam-formation, means for limiting the movement of said carrier-arm, and means for biasing said work-folding scroll into cooperative position with said arbor.

2. A sewing machine hemming attachment comprising a base-member, an arbor fixed to said base-member and disposed so that its free end extends substantially in the normal direction of feed, a work-folding scroll complementary to said arbor, a carrier arm fulcrumed upon said

base-member and supporting said work-folding scroll for arcuate movement relative to said arbor generally in a direction inclined rearwardly and away from the normal line of seam-formation, means for limiting the arcuate movement of said carrier-arm, and a spring for yieldingly maintaining said work-folding scroll in cooperative work-folding relation with said arbor.

3. A hemming attachment comprising a base-member, an arbor fixed to said base-member and disposed so that its free end extends substantially in the normal direction of feed, a work-folding scroll complementary to said arbor, a carrier-arm fulcrumed upon said base-member and supporting said work-folding scroll, a pivot-stud projecting through said carrier-arm and threaded into said base-member in position so that the work-folding scroll in its movement relative to said arbor shifts in a direction inclined rearwardly and away from the normal line of seam-formation, means for limiting the movement of said scroll, and a spring-wire for biasing said work-folding scroll into cooperative relation with said arbor, said spring-wire being coiled about said pivot-stud and having one of its ends anchored in said carrier-arm and the other of its ends anchored in said base-member.

4. A hemming attachment comprising a base-member, an arbor fixed to said base-member and disposed so that its free end extends substantially in the normal direction of feed, a work-folding scroll complementary to said arbor, a carrier-arm fulcrumed upon said base-member and supporting said work-folding scroll and having formed therein an elongated aperture, a pivot-stud projecting through said carrier-arm and threaded into said base-member in position so that the work-folding scroll in its movement relative to said arbor shifts in a direction inclined rearwardly with respect to the normal direction of feed of the work through the attachment, means for limiting the movement of said scroll including a stop-screw projecting through said elongated aperture in said carrier-arm and threaded into said base-member, and a spring for biasing said work-folding scroll into cooperative relation with said arbor.

5. A presser-foot hemmer having a sole-plate provided with a needle-hole and at its forward end with spaced toes, an arbor carried by one of said toes, a work-folding scroll complementary to said arbor and having a spiralled leading edge extending rearwardly in the space between said toes, a lateral extension provided on said sole-plate adjacent the other of said toes, a carrier-arm fulcrumed upon a pivot-stud threaded into said extension and formed at one end with an elongated aperture and supporting at its other end said work-folding scroll, a stop on said lateral extension projecting through said elongated aperture and cooperating with the opposite ends thereof to limit the pivotal movement of said carrier-arm, and a spring for maintaining said work-folding scroll in cooperative relation with said arbor.

JOHN P. ENOS.
